CONTAINER FOR STERILIZED ARTICLES

Edward Johnson, Montclair, N. J., assignor to
Meinecke & Company, New York, N. Y., a corporation of New Jersey

Application September 16, 1932, Serial No. 633,416

1. Claim: (Cl. 312—70)

It is well-known that in performing surgical operations, the surgeon's hands must be absolutely sterilized. In order to accomplish that result, it is necessary to use a hand-brush which has been thoroughly and completely sterilized.

5 My invention consists of a receptacle for holding a number of sterilized brushes and it is so constructed that the container with the brushes inside can be placed in an autoclave or sterilizing vessel with the brushes inside of it and both the container itself and the brushes can be thoroughly sterilized. It comprises means for ejecting the sterilized brushes one at a time as required by the user by simply pressing a lever so that a sterilized brush will drop into his hands without having previously come into contact with any undesirable and unsterilized material.

10 The container in its preferred form is built to hold approximately a dozen brushes, although it may be longer if desired. The invention also comprises a particular form of brush, means for visually indicating whether the container requires refilling and means for detachably securing it to the wall of a room.

15 25 In the accompanying drawings, Fig. 1 shows a near-side view of a container with housing broken away to show four brushes therein.

Fig. 2 is a front view of the same.

20 Fig. 3 shows a catch for holding the glass cover of the sight hole.

30 Fig. 4 shows one view of a detail of the means for actuating the device.

Fig. 5 shows a far-side view of the container with the cover broken away to show the mechanism for removing the brushes.

35 Fig. 6 shows means for securing the container to the wall.

Figs. 7 and 8 are detailed views of the means for releasing the brush.

40 Fig. 9 shows a cover for placing over the operating means.

Fig. 10 is a side view of the same to show the catch for holding the cover on the container.

45 Fig. 11 is a detailed view of the means for holding the container on the wall.

The device consists essentially of a container 12 rectangular in form having one side 13 on hinges, so that it can be opened in order to place the brushes 14 in the container. As shown in Fig. 2, the device has an opening 15 at one side near the bottom thereof over which is placed a piece of glass 16 through which it can be ascertained whether or not the device needs refilling with brushes. In Fig. 3 is shown a swinging slotted latch member 17 pivotally connected at

18 to the side of the container. The pivot is preferably in the form of a set-screw with a knurled head so that when the screw is turned, the latch member is loosened and swung to one side and the glass member inserted. The latch member 17 is then swung back to a right-angle position with the side of the container and the screw tightened.

15 The brushes are held in position by one end of the brush resting on a stop-bar 19 at the side of the container (see Fig. 1). The other end of the brush rests on an escapement member 20 preferably having four vanes as shown in Fig. 1. This escapement member 20 is contained in a semi-circular housing 21 secured by set-screws 22 to the front and bottom of the container. The escapement member 20 is mounted on a shaft 20^a one end of which is journaled in the casing 21. The other end of the escapement member shaft extends through the contiguous side of the casing member 21 and has rigidly secured on that end of it a ratchet 22A (seen in Figs. 4, 7 and 8). A rocker-arm 23 is mounted at 24 at the side of the casing 21. To the rocker-arm is pivotally connected at 25, a lever 26. The other end of the lever 26 is pivoted at 27 to another lever 28 pivoted at 29 to the bottom of the casing. The lever 28 operates against a coiled spring 30 located between a projecting end 31 of the casing and said lever.

20 25 30 35 40 45 50 55 60 65 70 75 80 85 90 95 100 105 110 The device operates in the following manner. When the lever 28 is pressed by hand, it throws the lever 26 forward and the lower part of the rocker-arm 23 is released from the lower part of the ratchet, whereas the upper part of the rocker-arm comes in connection with another face of the ratchet best seen in Fig. 4 and pushes it part way around. Complete rotation of the ratchet to the desired degree and turning of the escapement member 20 to release the brush 14 is effected by the wiping of the lower part of the rocker arm on the ratchet upon the return movement of lever 28 to its inoperative position, as shown in Fig. 8. As that end of the brush is released there is, of course, nothing to hold it in the casing, and it slips right off of rod 19 into the hand of the user. It will, of course, be understood that the hand-lever 28 may, if desired, be so constructed as to connect with a foot actuated means for operating the device. The operating means just described are hidden from view and prevented from collecting dirt by a cover 32 secured to the side of the container by a spring catch member 33, clasping the cover over the side of the container and the other end of the

cover 32 is connected by a set-screw 34 to the casing which holds the escapement member.

- The invention also comprises a new form of brush which, as shown by the numeral 14 in Fig. 1, has depressions or indentations 35. The brushes are made with wooden backs and when sterilized have a tendency to swell considerably. It is, of course, necessary to have them held as firmly as possible in position in the container.
- 10 In order to accomplish that end, the container has a ridge 36 pressed both into the side of the casing and the door, and this ridge 36 engages with the depression 35 in the side of the brush and holds each brush in alignment.
- 15 The invention also comprises the following means for securing the receptacle to the wall of a room. At the top and bottom of the back of the container is secured an extension 37 preferably about an inch and a half both above and below the top and bottom of a container. Each of these extensions has a keyhole slot 38 for engaging the head of a screw 39 which is fastened into a member, preferably of wood 40. The strip or member 40 may be nailed or screwed to the 25 wall of a room. At each end of the member 40 is a spring clamp 41 having an aperture 42 through which extends a screw 39. The keyhole slot 38 in each of the extension members 37 fits over the screw head and the tension of the spring clamp 41 holds the container firmly in position.

I claim:—

A container for sterilized articles comprising a casing, an opening in the bottom of said casing, means at the rear of said casing and near the bottom thereof for holding one end of an article, a housing in the opposite side of said casing, a shaft journaled in said housing, an escapement member secured on said shaft for holding the other end of said article, a ratchet mounted on said shaft adjacent the escapement member, an oscillating rocker arm pivotally mounted at the lower end of the casing, one prong of said rocker arm engaging the ratchet member, a spring controlled lever pivotally mounted at the lower part of the casing, a link connecting said spring controlled lever and said rocker arm whereby pressure exerted on the spring controlled lever will cause the rocker arm to oscillate sufficiently to release the lower prong of the rocker arm from the ratchet whereby one end of the article resting on the escapement member will be released and fall through the opening and at the same time the upper prong of the rocker arm will advance the ratchet and escapement member one step so that when pressure is released on the spring controlled lever one end of the next succeeding article will rest upon the escapement member.

EDWARD JOHNSON.
